[57] CLAIM

The ornamental design for a combined wristwatch and
strap, as shown and described.

DESCRIPTION

FIG. 1 front elevational view of a combined wristwatch
and strap showing my new design;

FIG. 2 is a right side elevational view;

FIG. 3 is a rear elevational view;

FIG. 4 is a left side elevational view;

FIG. 5 is a top plan view;

FIG. 6 is a bottom plan view;

FIG. 7 is a right side elevational view, with the strap
shown in an open position; and

FIG. 8 is a bottom and right perspective view thereof,
with the strap shown in an open position and the watch
being omitted for ease of illustration.

FIG. 4

FIG. 3

FIG. 2

FIG. 1

FIG. 7

FIG. 8
